JACOB MORRIS, OF MOORE PARK, NEAR SYDNEY, AND SOLOMON ADOLPHUS BRISBANE MARKS, OF POTTS POINT, NEAR SYDNEY, NEW SOUTH WALES, AUSTRALIA.

LADY'S HAT-FASTENING.

933,659.

Specification of Letters Patent. Patented Sept. 7, 1909.

Application filed October 17, 1908. Serial No. 458,319.

To all whom it may concern:

Be it known that we, JACOB MORRIS, canister manufacturer, and SOLOMON ADOLPHUS BRISBANE MARKS, indent and commission agent, subjects of the King of Great Britain, and residents, respectively, of No. 432 Park road, Moore Park, near Sydney, in the State of New South Wales, Commonwealth of Australia, and No. 4 Challis avenue, Potts Point, near Sydney, aforesaid, have invented certain new and useful Improvements in Ladies' Hat-Fastenings, of which the following is a specification.

Owing to the liability of ordinary hat-pins working loose and falling out, considerable difficulty is experienced, as is well-known, by ladies in retaining their hats securely on their hair, in addition to which it is necessary that the hat-pins at present in general use must be handled with care to avoid accidents to the wearers and others.

Now this invention has been designed in order to provide a simple and reliable fastening for securing ladies' hats in a wearing position to their hair, and which fastening will permit of the position or set of the hat being easily and quickly altered at any time without causing the wearer any inconvenience. Moreover, the construction of the fastening is such that, when once it has been secured to a hat, it cannot become detached, while the liability to accidental injury by hat fastenings is entirely obviated.

In order that the invention may be readily understood, it will now be described with reference to the accompanying sheet of illustrative drawings forming part of this specification, and in which:—

Figure 1 is a perspective view of the improved fastening, partly open preparatory to securing the hat (indicated by broken lines) to the wearer's hair. Fig. 2 is a front elevation of a lady's hat partly cut away and illustrating the fastening in its normal position. Fig. 3 is a similar view of a lady's hat also partly cut away and illustrating a modification in the improvements. Figs. 4 to 12 are constructional detail views to be hereinafter described.

The fastening consists essentially of two combs *a* constructed of any preferred material and shape. Each of these combs is

secured by an elastic connection as a tension spring *b* (or elastic cord) and staple *c* to the center of the top member of a substantially U-shaped frame *d*. This frame is made of thin steel but if preferred, it may be made of any other flexible material that will readily bend into the shape of the hat crown in the manner shown in Fig. 1 of the drawings.

Each comb *a* is provided with a double rod *e* which is secured at one end to and projects at right angles from the center of the back thereof. These double rods *e* pass through suitable holes *f* formed in the side members of the frame *d* and then through opposite sides of the crown of the hat. The outer end of each of the said double rods is fitted with a suitable form of plain or ornamental gripping button as *g* which may be soldered, screwed or otherwise affixed thereto—see Figs. 5, 8, 9, and 10. The purpose of forming the rods *e* double is to better insure the fastening combs *a* retaining their correct horizontal position under all ordinary conditions.

The side members of the frame *d* are provided at suitable points with holes *h*, which enable the frame to be sewn or otherwise conveniently secured to the sides of the hat crown, while the ends of the side members are ordinarily formed with serrations or teeth *i*, or be V-pointed, and then bent outwardly to engage with the inner sides of the hat crown. The purpose of the frame *d* is to take up the strain necessary to operate the fastening, and to effectually prevent the hat from being pulled out of shape, in addition to which it serves to protect the hat lining.

The rods *e* may be readily attached to the combs *a* by arranging their ends to pass through holes suitably formed therein, and then bending them at right angles and backward as shown in Figs. 1 and 2 of the drawings.

In the modification illustrated in Fig. 3, the frame *d* is dispensed with, and the staple *c* is shown secured approximately to the center of the top of the crown of the hat. The springs *b* are connected to the combs *a* in the same manner as indicated in Fig. 2. The fastening combs in this instance may

be of the ordinary "shell" or curved type, and be connected to their respective gripping buttons *g* by a single rod *j*, or the rod and comb may be formed integral as shown 5 in Fig. 7.

The button *g* illustrated in Figs. 8 and 9 may be formed spherical as shown (or given any other preferred shape) and is made in 10 two parts *k* and *l*. The lower part *l* is provided with an upwardly projecting stud *m*, which screws into or otherwise engages with a hole *n* formed in the upper part *k*. The outer end of the rod *j* is formed with 15 a loop *o*, which is passed around the stud *m* on the lower part *l*. A groove *p* is formed in one or both of the contiguous faces of the two parts of the gripping button for the purpose of receiving the looped end of the rod *j* when affixed thereto.

Fig. 11 illustrates a modification in the construction of the frame *d* designed in order to permit its better adjustability to hats of varying sizes and forms. In this case, the frame is made in two parts of 25 similar construction having their inner ends enlarged and provided with a slot *q* slightly larger in size than the width of the frame *d*. A series of holes *r* is formed in the inner end of the two parts of the frame, and their 30 outer ends are furnished with holes *f* and *h* similar to and for the same purpose as those hereinbefore described. The two parts of the frame *d* are connected together by passing the outer end of the one through 35 the slot *q* formed in the inner end of the other, when the outer ends are pulled outwardly until the frame is of the length required. To secure the two parts of the frame immovably together, the shank of a 40 rivet *c* is inserted through corresponding holes *r* in the center of the frame midway between the enlarged ends of both of its parts. This said rivet *c* is formed with a 45 ring on the head, to which is secured the ends of the springs *b*.

A further modification in the constructional details of the frame *d* is illustrated in Fig. 12, in which view the top member is shown as made of flexible wire *s* having each end 50 affixed by any approved means to the side members *t* in which are formed holes *f* and *h* for the same purpose as above described with reference to the same letters in Figs. 4 and 11. The center of the top member *s* 55 is formed with a loop or ring *c* for affixing thereto the ends of the springs *b*. The wire *s* forming the top member of the frame *d* is bent to conform to the shape of the hat to which the fastenings are to be applied, but 60 normally it is straight in order that it may be bent into any desired shape.

To attach the improvements as illustrated in Figs. 1 and 2 to a hat, the tension springs *b* are first affixed by means of the staple *c*

to the center of the top member of the 65 frame *d*, which is then sewn within the crown of the hat as shown. The rods *e* are passed through their respective holes *f* in the said frame and through the sides of the crown. The combs *a* and the outer ends 70 of the springs *b* are then connected to the inner ends of the said rods *e* in any convenient manner.

When the frame *d* is not employed—see Figs. 2 and 3—the ends of the rods *e* are 75 simply passed through the sides of the crown, eyelets being ordinarily secured to the hat for the purpose, and then connected to their respective fastening combs and springs. 80

To secure the hat to the hair of the wearer, the rods *e* and combs *a* are pulled outwardly into the positions shown in Figs. 1 and 3 by means of the gripping buttons *g*. The hat is then adjusted in the right position on the 85 head, when the springs *b* are allowed to draw the combs *a* inwardly until they are firmly in engagement with the hair. To remove the hat, the wearer merely draws the gripping buttons *g* outwardly until the 90 combs *a* to which they are connected, have been freed from the hair when the hat can be lifted off without deranging the hair.

It will be readily understood that a nice 95 adjustment of the hat may be obtained by the improved fastenings, as, when the hat is once placed in the correct position, the releasing of the buttons *g* will cause it to be instantly secured in such position.

What we do claim is:—

1. A hat fastening comprising a substantially U-shaped frame, rods slidably mounted upon the side members of said frame, combs secured to the inner ends of the rods, and elastic elements secured to the combs 105 and to the top member of said frame.

2. A hat fastening comprising a U-shaped frame, rods slidably mounted upon the side members of said frame, combs secured to the inner ends of said rods, and elastic elements secured to said combs and to the top member 110 of said frame.

3. A hat fastening comprising a frame consisting of adjustably connected sections, rods slidably mounted upon the frame, 115 combs secured to said rods, and elastic elements secured to said combs and to said frame.

4. A hat fastening comprising a sectional frame, means adapted to secure the sections of said frame together, rods slidably mounted upon said frame, combs secured to said rods, and flexible elements secured to said 120 combs and to said frame.

5. A hat fastening comprising a U-shaped 125 frame, the top member of said frame being constructed of wire, rods slidably mounted upon the side members of said frame, combs

secured to the inner ends of said rods, and elastic elements secured to said top member and to said combs.

6. A hat fastening including a rod, a comb secured to one end of the rod, and a gripping button secured to the other end of the rod, said gripping button consisting of separable sections secured together and to said rod by a stud.

In witness whereof we have signed this 10 specification in the presence of two witnesses.

JACOB MORRIS.

SOLOMON ADOLPHUS BRISBANE MARKS.
